ATTORNEY

UNITED STATES PATENT OFFICE.

DANIEL C. STOVER, OF FREEPORT, ILLINOIS.

WIRE-BARBING MACHINE.

SPECIFICATION forming part of Letters Patent No. 298,131, dated May 6, 1884.

Application filed May 9, 1883. (No model.)

To all whom it may concern:

Be it known that I, DANIEL C. STOVER, a resident of Freeport, in the county of Stephenson and State of Illinois, have invented certain new and useful Improvements in Wire-Barbing Machines; and I do hereby declare the following to be a full, clear, and exact description of the invention, such as will enable others skilled in the art to which it pertains to make and use the same.

My invention is an improved machine for attaching certain forms of wire barbs to two-strand fence-cables. Its details are fully described in the following specification and shown in the accompanying drawings, in which—

Figure 1 is a plan of the machine; Fig. 2, a front elevation thereof; Fig. 3, a side elevation of the barb-forming sleeve and spindle, with bearings and gearing; Figs. 6, 5, and 4, perspective views of the stationary spindle Q, the sleeve O, which rotates thereon, and the hook-carrying collar N, which turns with said sleeve; Figs. 7, 8, and 9, front elevations of the spindle, sleeve, and collar in their successive positions in the formation of a barb; Fig. 10, a horizontal projection of the same parts in the position shown in front elevation in Fig. 8; Fig. 11, a horizontal projection of the same parts in the position shown in front elevation in Fig. 7; and Fig. 12, a front elevation of the forked lever E', which imparts longitudinal motion to the collar N.

In these views, A is the bed of the machine, B its driving-shaft, and B' a side shaft connected with the driving-shaft by miter-gears. The shaft B' carries two rigidly-mounted cams, C C', the first of which imparts reciprocal rotary motion in a vertical plane to the segmental gear X, while the second imparts vibratory motion in a horizontal plane to the forked lever E'. The segment X moves about the shaft F as an axis, and the lever E' swings about a pivot in the vertex of the post F' as a center.

Near the center of the bed, and in a line parallel to the side shaft, B', are rigidly attached to the bed two vertical posts, H H', in which is journaled near the face of the bed the horizontal shaft G. A pinion, I, is rigidly

mounted on the shaft G between the posts H H', and a second and larger pinion, I', is rigidly mounted on said shaft in front of the post H'.

Above the pinion I' is a horizontal spindle, 55 Q, formed integrally with the post H', or rigidly attached to its face, both post and spindle being longitudinally perforated for the passage of two main wires to be barbed. On the spindle Q rotates freely a sleeve, O, on 60 which is rigidly mounted a pinion, I'', which engages with the pinion I' immediately below it, and on the sleeve O is a collar, N, attached to the sleeve by means of a key, which permits longitudinal motion of the collar on the 65 sleeve, but not rotary motion. A groove, L, is cut in the periphery of the collar, and in this groove lie the ends of the fork J at the inner end of the lever E'. At the front end of the collar N is a radial hook, K, extending 70 inward toward the center, and provided at its inner end with a horizontal wrapping-pin, P, extending from the hook toward the plane of the face of the collar, the distance from the end of the wrapping-pin to the plane of the 75 face being not less than the thickness of the barbing-wire.

From the drawings and the foregoing explanation it is plain that the rotation of the driving-shaft, shaft B', and cams C C' will 80 produce reciprocal rotary motion of the sleeve O and reciprocal longitudinal motion of the collar N on the sleeve, and that, whatever rotary motion may be communicated to the sleeve, the collar will rotate with it. It is 85 also a matter of course that the driving-cams may be so "timed" as to produce the various motions in any desired order.

The operation of the parts in forming a barb is shown in Figs. 7, 8, 9, and 10, and is as follows: The barb-wire R is fed between the main wires, at right angles thereto and just in front of the face of the sleeve and spindle, the free end S of the barb-wire lying immediately under the hook K, as shown in Fig. 7, and the 95 collar N being drawn back on the sleeve O, so that the end of the wrapping-pin P rests against the face of the sleeve, as shown in Fig. 11. The sleeve O, with the collar N and pin P, is then rotated in the direction indicated by the arrow 100

in Fig. 7 through an angular space of four hundred and fifty degrees, or one and one-fourth revolution, until the hook reaches the position shown by the dotted lines in Fig. 8 and the barb assumes the form shown in Fig. 8. The barb is then severed and the sleeve rotated in the direction indicated by the arrow in Fig. 8 until it reaches the end R of the barb, the collar being at the same time moved forward on the sleeve until their faces are flush and there is a distance between the end of the wrapping-pin and the face of the sleeve equal to the diameter of the barbing-wire. This brings the parts into the position shown in Fig. 10, when a further rotation of the sleeve in the direction indicated by the arrow in Fig. 8 through an angle of two hundred and seventy degrees carries the end R into the position shown in Fig. 9 and completes the barb. In making the last wrap, the hook K passes around the point S of the barb, the space between the end of the wrapping-pin and the face of the spindle being sufficient to permit the end R to pass through it, as the end of the barb lies in close contact with the face of the sleeve. It is evident that the hook K need not necessarily be attached to a collar encircling the sleeve O, but may be attached to the sleeve in any other way that will allow it longitudinal but not rotary motion independent of the motion of the sleeve—as, for instance, by forming the hook with a straight shank of polygonal form sliding in a corresponding groove in the sleeve—and that various devices may be employed to give it longitudinal motion. The hook K, as shown and described, is provided with a wrapping-pin, P, extending from the end of the hook inward toward the face of the sleeve O. This wrapping-pin may, however, be dispensed with by giving the hook sufficient thickness to afford a proper bearing-surface for wrapping the barb. No novelty is claimed for the devices used to rotate the barb-forming parts of this machine, as the cams and gearing shown are old and well-known mechanical expedients.

Having, however, described my invention and explained its operation, what I claim as new, and desire to secure by Letters Patent, is—

1. In a wire-barbing machine, the combination of a spindle perforated longitudinally for the passage of the main wires, a sleeve rotating freely on said spindle, and a barb-wrapping hook attached to and rotating in unison with said sleeve, but having longitudinal motion independent thereof, whereby it is adapted to wrap one of the ends of a barb in a coil arranged next to the face of the sleeve and spindle, and the other end in a second coil continuous with the first, but arranged farther from said face. 60
2. In a wire-barbing machine, the combination of a spindle longitudinally perforated for the passage of the main wires, a sleeve rotating freely on said spindle, a collar encircling said sleeve and rotating therewith, but having longitudinal motion independent thereof, a barb-wrapping hook rigidly attached to said collar, and adapted to wrap one end of a barb in a coil arranged next to the face of the spindle, and the other end in a second coil continuous with the first, but arranged farther from the face of the spindle, and means for imparting reciprocal longitudinal motion to said collar. 7c

3. The combination of the longitudinally-perforated spindle Q, the sleeve O, rotating thereon, the collar N, keyed to said sleeve and rotating therewith, but free to move longitudinally thereon, the hook K, rigidly attached to said collar, the forked lever E, engaging with the annular groove L in the collar N, and means for imparting reciprocal motion to said lever, whereby reciprocal longitudinal motion is imparted to said collar, substantially as shown and described, and for the purpose set forth. 85

In testimony whereof I have signed this specification in the presence of two subscribing witnesses.

DANIEL C. STOVER.
